UNITED STATES PATENT OFFICE.

EDWIN E. SAUZE, OF WALLA WALLA, WASHINGTON.

DESIGN FOR A CALCULATOR.

43,451.

Specification for Design.

Patented Jan. 14, 1913.

Application filed September 25, 1912. Serial No. 722,375. Term of patent 7 years.

To all whom it may concern:

Be it known that I, EDWIN E. SAUZE, a citizen of the United States, residing at Walla Walla, in the county of Walla Walla and State of Washington, have invented a new, original, and ornamental Design for Calculators, of which the following is a specification, reference being had to the accompanying drawing, forming a part there-

of, in which drawing a plan view of the invention is shown.

I claim:

The ornamental design for a calculator, as shown.

EDWIN E. SAUZE.

Witnesses:

J. G. THOMAS,
C. M. CANFIELD.
